(57) CLAIM

The ornamental design for a fashion ornament, as shown and described.

DESCRIPTION

FIG. 1 is a front perspective view of a fashion ornament showing my new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a front perspective view of the fashion ornament shown in FIG. 1, shown in the environment of a handbag;

FIG. 8 is a front perspective view of the fashion ornament shown in FIG. 1, shown in the environment of a belt; and,

FIG. 9 is a front perspective view of the fashion ornament shown in FIG. 1, shown in the environment of a footwear. The broken lines in the drawings represent portions of the fashion ornament and form no part of the claimed design. The other broken lines in FIGS. 7, 8 and 9 represent environmental subject matter only and form no part of the claimed design.

1 Claim, 7 Drawing Sheets
